UNITED STATES PATENT OFFICE.

JOHN M. BAKER, OF NELSON, MISSOURI, ASSIGNOR OF ONE-FOURTH TO
IRVIN WILLIAMS, OF SAME PLACE.

BROADCAST SEEDER.

SPECIFICATION forming part of Letters Patent No. 683,545, dated October 1, 1901.

Application filed March 2, 1901. Serial No. 49,618. (No model.)

To all whom it may concern:

Be it known that I, JOHN M. BAKER, a citizen of the United States, residing at Nelson, in the county of Saline and State of Missouri, have invented a new and useful Broadcast Seeder, of which the following is a specification.

My invention is an improved broadcast seeder for sowing grass, grain, and other seeds; and it consists in the peculiar construction and combination of devices hereinafter fully set forth and claimed.

In the accompanying drawings, Figure 1 is a perspective view of a broadcast seeder constructed in accordance with my invention. Fig. 2 is a detail transverse sectional view of the same. Fig. 3 is a detail top plan view of a portion of the adjustable bracket. Fig. 4 is a side elevation of a modified form of my invention. Fig. 5 is a transverse vertical sectional view of the same.

In the embodiment of my invention I provide a frame 1, which resembles the frame of a wheelbarrow. A shaft 2 is journaled in bearings near the front ends of the side bars 3 of the frame. Said shaft has a traction and supporting wheel 4. A friction - disk 5 revolves with said wheel 4. Cross-bars 6, 7 connect the side bars 3 of the frame, and at the rear ends of said side bars are formed suitable handles 8, by means of which the machine may be readily trundled as a barrow. Supporting-legs 9 on the under sides of said bars 3 maintain the frame in a horizontal position when the machine is not in operation.

A bracket 10 has a foot 11, a horizontally-disposed inwardly-extending arm 12, and a curved arm 13, which is disposed over said arm 12. The foot of the bracket is provided at its ends with transverse slots 14 of suitable length. Screws or bolts 15 in said slots secure the foot of the bracket on one of the side bars 3 near the front end of the latter, said screws or bolts and said slots adapting the bracket to be laterally adjusted, as will be understood. A vertical shaft 16 is journaled in a bearing 17, with which the arm 13 is provided, and has its lower end stepped in a bearing 18 at the inner end of the arm 12. Said shaft has at its upper end a feed-worm

19 and a stirring-pin or other suitable device 20. Below the feed-worm and on the said shaft is a revoluble broadcasting disk 21, which is concavo-convex in form, its upper side being concaved, and said broadcasting disk is provided with a series of radial arms 22 on its upper side. Said disk is secured to and rotates with the said shaft 16. On the latter is a vertically-adjustable friction-wheel 23, which engages the friction - disk 5, and hence imparts rotary motion to the shaft 16, the broadcasting disk 21, and the worm 19 when the machine is in operation. A set-screw 24 or other suitable device is employed to secure the said friction-wheel 23 to said shaft 16 at any desired adjustment. By moving said friction-wheel 23 toward or from the center of the disk 5 the speed of the shaft 16, and hence of the broadcasting disk and of the feed-worm, may be increased or decreased, as 70 may be required. Hence the quantity of seeds broadcasted over a given area may be predetermined and regulated at will. The requisite degree of compression between the friction-disk 5 and friction-wheel 23 to insure 75 the rotation of the latter is obtained by adjusting the bracket 10 by the means and in the manner hereinbefore described.

A hopper 25 is supported above the front end of the frame 1 by supporting-rods 26, 80 which connect the same to the front ends of side bars 3 and to the center of the cross-bar 6. A vertical tubular spout 27, which depends from the lower end of the hopper and through which the contents of the hopper are 85 discharged, forms a casing for the feed-worm 19. The latter rotates therein, and hence feeds the seeds from the hopper to the broadcasting disk, as will be understood.

It will be understood from the foregoing 90 and by reference to the drawings that the broadcasting apparatus is disposed in an elevated position above the front end of the main frame and that the latter by reason of its open construction offers practically no obstruction to the seeds as the same descend to the ground, and it will be further understood that the seeds fall to the ground in advance of the operator who trundles the machine, so that his body offers no obstruction 95 100

to the seeds in their passage to the ground. Hence the seeds are scattered evenly and uniformly, as will be understood.

While I have hereinbefore described and shown friction-gears for rotating the broadcasting disk, I do not limit myself to this means for rotating the disk, as any other form of gears may be substituted for friction-gears without departing from the spirit of my invention.

In Figs. 4 and 5 I show a modified form of my invention in which the hopper 25^a has on its lower side a horizontally-disposed feed-tube 19^a. In the bottom of the hopper is an opening 28, through which seeds are discharged onto a horizontally-disposed worm 27^a in said feed-tube. A cut-off plate 30 operates on the bottom of the hopper and is adapted to entirely close the opening 28 to 15 cut off the discharge of seeds from the hopper or to open the same to any desired extent, and hence regulate the quantity of seeds discharged from the hopper. An operating-rod 31 is provided for the cut-off 30 and extends through one end of the hopper, as shown. At the outer end of a shaft 32, which projects from one end of the feed-worm, is a pulley 33. The latter is connected to the axle 2 by an endless belt or cord 34, and hence the 20 feed-worm is driven from the axle, as will be understood. Other modifications may be made within the scope of my invention.

Having thus described my invention, I claim—

1. In a broadcast seeder, the combination of a frame, a traction-wheel, a friction-disk revoluble therewith, an adjustable bracket, a vertical shaft guided in said bracket and carrying a revoluble broadcasting disk, a friction-wheel adjustable on said shaft and co-acting with said friction-disk, and means to discharge seeds onto said revoluble broadcasting disk, substantially as described.

2. The combination in a broadcast seeder, of a revoluble broadcasting disk, means to rotate and vary the speed thereof, a hopper, a revoluble feed-worm to convey seeds therefrom to said broadcasting disk, means to rotate and vary the speed of said feed-worm, and means to regulate the supply of seeds to said feed-worm, substantially as described.

3. In a broadcast seeder, the combination of a frame, a traction-wheel, a friction-disk revoluble therewith, an adjustable bracket, a vertical shaft guided in said bracket and carrying a revoluble broadcasting disk, a friction-wheel on said shaft and coacting with said friction-disk, and means to discharge seeds onto said revoluble broadcasting disk, substantially as described.

In testimony that I claim the foregoing as my own I have hereto affixed my signature in the presence of two witnesses.

JOHN M. BAKER.
